UNITED STATES PATENT OFFICE

2,651,122

POSITIONING APPARATUS FOR
DREDGE PIPES

Roy A. Brinkman, Oak Park, Ill., assignor to Construction Aggregates Corporation, a corporation of Delaware

Application July 25, 1951, Serial No. 238,555

4 Claims. (Cl. 37—72)

1

This invention relates to conveying apparatus and more particularly to apparatus for positioning equipment relative to the side of a ship.

In recent years, land reclamation and the establishment of stock piles of sand or other free flowing material has become increasingly important. An efficient and economical method for accomplishing the above is to suck a mixture of sand or other free flowing material and water from the bottom of a body of water into hoppers of a sand carrying ship, dewater this sand and transport it to a landing berth where pipe lines on shore are connected to the ship. Water is then added to the sand contained in the hoppers and a mixture of sand and water pumped from the ship to the desired areas through the pipe lines on shore.

In hydraulically loading the hoppers of a sand carrying ship, the mixture of free flowing material and water is sucked from the bottom of the sea through a long, heavy suction pipe, the lower end of which is located at the bottom of the sea and the upper end connected to an intake opening in the side of the ship. The mixture is then conducted through a pipe leading from the intake opening to a suction pump and from there discharged into the hoppers. When not in use, the suction pipe is disconnected from the intake opening, raised along the ship's side and then moved inboard where it is kept until the ship is ready for reloading, at which time the above procedure is reversed. In the past, the apparatus for positioning this long, heavy pipe and aligning its upper end flush with the intake opening was very cumbersome and its operation time consuming.

This invention provides a greatly improved positioning apparatus, whereby the suction pipe can be rapidly and easily moved outboard, lowered along the ship's side, and its upper end aligned flush with the intake opening located in the side of the ship. Further, the positioning apparatus is so adapted as to keep the upper end aligned and flush with the intake opening during the entire loading period so that an actual connection between the upper end of the suction pipe and the intake opening is unnecessary. All of these operations are accomplished in two separate, sequential steps.

The invention is illustrated in a preferred embodiment in the accompanying drawings, in which:

Figure 1 is a fragmentary, elevational view looking toward the side of the ship showing the front of the apparatus with parts removed for purposes of clarity;

2

Figure 2 is a fragmentary, sectional view taken along line 2—2 of Figure 1 illustrating the suction pipe in two positions;

Figure 3 is a fragmentary, sectional view of the upper portion of Figure 2 showing the carriage in an inboard position;

Figure 4 is a fragmentary, plan view of the apparatus with the carriage in the position of Figure 3;

Figure 5 is a fragmentary, sectional view taken substantially along line 5—5 of Figure 4;

Figure 6 is a fragmentary, sectional view taken along line 6—6 of Figure 5 and showing in addition a fragmentary, diagrammatical view of the winch; and

Figure 7 is a generally horizontal, sectional view taken substantially along line 7—7 of Figure 5 and showing a portion of the rear of the carriage.

The positioning apparatus consists generally of a way 10 for carrying a movable carriage 11 mounted thereon. This way is so mounted on a deck 12 of a sand carrying ship as to extend inwardly from a side 13 of the ship with one end substantially adjacent thereto. The carriage 11, having a face 14, is adapted to travel over the way in such a manner that the face can be moved from a position substantially aligned with the side 13 of the ship to a position inwardly therefrom. The upper portion 16 of a guideway 15 is mounted on the face 14 of the carriage and a lower portion 17 secured to the side 13 of the ship. These portions are divisible from each other so that a plate 44 positioned for travel along the guideway 15 can be moved by appropriate means along the side of the ship in the lower portion 17 of the guideway and when located in the upper portion 16, can be moved on the carriage 11 inwardly from the side 13.

Referring to the drawings in greater detail, the sand carrying ship, portions of which are shown, has a main deck 12, a second deck 12a, and a side 13 in which is located an intake opening 18 leading to a suction dredge pump not shown in the drawings. Mounted on the deck 12 of this ship is the way 10 composed of two parallel I-beams 19 which provide the support for the slidably movable carriage 11 mounted thereon.

As best seen in Figs. 2—5 and 7, the I-beams 19 extend inwardly from the side 13 of the ship and at an upward slope therefrom, the lower ends being substantially aligned with the side 13. It is preferred that the angle of slope be such that gravity will cause the carriage 11 to slide downward over the I-beams 19.

Support members 21a, 21b, and 21c extending upwardly from decks 12 and 12a together with parallel bracing members 22a, 22b, and 22c extending between the I-beams 19 hold these beams in a rigidly fixed, sloping position and keep them in alignment. In the preferred embodiment, the bracing members are in the form of steel channels, the end portions of which are secured to the I-beams 19 as by welding. Bracing member 22a also supports a sheave block 43 which is secured thereto and contains sheave K, rotatably mounted on the shaft 43a of the block. The two bracing members 22b and 22c, located in the rear portion of the way 10, serve as a support for two parallel, spaced cross channels 23a and 23b which extend therebetween and upon which is mounted the double sheave block 24. This block contains two sheaves, F and I, rotatably mounted on the sheave shaft 24a. To carry the thrust from the double sheave block 24 to the supporting member 21b when the positioning apparatus is in operation, parallel channels 25 are provided and extend between bracing members 22b and 22a, the latter being secured to the supporting member 21b.

In positioning the I-beams 19, it is preferred that their bottom flanges 26 face the floor of the main deck 12 so that the carriage 11 may be adapted to slide over the top flanges 26a of the I-beams 19.

The carriage 11 which is slidably mounted on the top flanges 26a of the I-beams 19 is an absolutely rigid frame unit comprised of two identical, triangular shaped frame members, each slidably mounted on the top flanges 26a of the I-beams 19. Each of these frame members consist of a base angle 27a, a front angle 27b extending vertically from the front end of the base angle 27a, and a rear angle 27c extending between the back end of the base angle 27a and the top end of the front angle 27b. To form a strong, rigid structure, these steel angles are secured at their ends by gussets 28. The frame members are rigidly held upright in a spaced, parallel relation by a series of horizontally extending cross members, such as steel angles 29a, 29b and 29c, secured to the frame members by gussets 30. Cross members 29a and 29b form the top and bottom, respectively, of the front of the carriage 11 and cross member 29c forms the rear of the carriage.

The absolute rigidity of the carriage frame is due in a large measure to the triangular shape of the frame members. As a result, the carriage front which carries the heavy upper end of the suction pipe 31 when in an inboard position remains true as the carriage is moved over the way 10 and can always be aligned with the side 13 of the ship.

As best seen in Figs. 5 and 6, the carriage is slidably mounted on the top flanges 26a of the I-beams 19 by means of channels 32 and 33, atop which are positioned the base angles 27a. It is preferred that soft metal plates 34 such as brass, be inserted between the channels 32 and 33 and the surfaces of the top flanges 26a to reduce friction. In the particular embodiment shown, the plates 34 are secured to the channels 32 and 33.

To keep the carriage 11 from sliding off the I-beams 19 and insure continual alignment of the front of the carriage 11 with the side 13, the channels 32 and 33 are mounted over the top flanges 26a with their legs extending below the sides of the top flanges 26a. Keeper plates

35, secured to gussets 28, extend downwardly below the bottom flanges 26 and are bent under them to prevent the carriage from jumping off the I-beams 19 as best seen in Figs. 2 and 5.

Referring to Figs. 2-5 and 7, catch members 36a and 36b are mounted at the rear of the carriage frame 11 for the purpose of retaining the carriage 11 in its extreme lower or upper position on the I-beams 19. They are comprised of hook-shaped arms 37a and 37b rigidly secured to a shaft 38 pivotally mounted upon the carriage frame in end bearing plates 39a and 39b, respectively. The catch arms 37a and 37b are rocked manually by means of a lanyard 39 attached to a lever arm 40 secured to the center of the shaft 38 in order to permit the hook portions at the ends of the catch arms 37a and 37b to engage cooperating slots 41a, 41b, 41c and 41d in the top flanges 26a of the I-beams 19. Thus, the carriage 11 may be locked in position relative to the I-beams 19. One pair of slots, 41c and 41d are near the upper ends of the I-beam 19 as seen in Figs. 2, 3, 5 and 7 and similar slots 41a and 41b are near the low ends of the I-beams 19 to lock the carriage in its lowest position.

Referring to Figs. 1-6, a face plate 42, secured to the front of the carriage 11, as by welding, provides the support for the upper portion 16 of the guideway 15 in the form of a pair of centrally mounted, parallel tracks which extend downwardly along the face plate 42. Slidably mounted between the flanges of the upper tracks 16 is a fitting plate 44 which carries the upper end of the suction pipe 31. This plate has a hole 45 about which is an annular spacer 46 secured to the face plate 42. An annular retaining link 47 is mounted on the spacer 46, the spacer and retaining link forming an annular groove into which the flange 48 of the suction pipe elbow 49 is adapted to swivel. Thus, the upper end of the suction pipe 31 may be swiveled in a downward direction permitting the low end of this pipe to rest on the bottom of the sea while the ship is hydraulically loaded and when in the inboard position, as shown in Fig. 3, the suction pipe 31 may be positioned substantially parallel to the deck 12 of the ship. In order to further brace the plate fitting 44, a turn buckle brace 50 is connected between the outer part of the suction pipe elbow 49 and the top of the plate fitting 44.

A single sheave block 51 is secured to the top portion of the fitting plate 44 above the top ends of the upper tracks 16 by a bolt 51a which extends into the face of the fitting plate 44 and serves as a mount for the rotatable sheave B. Mounted above this sheave atop the cross member 29a of the carriage frame 11 are two sheave blocks 52 and 53 containing sheaves A and C, respectively, these sheaves being rotatably mounted on the shafts 52a and 52b of these blocks. All of the above sheaves form a part of the single line pulley system used to move the carriage 11 over the way 10 and the fitting plate 44 along the guideway 15.

Extending from cross member 29c at the rear of the carriage 11 to the center of the face plate 42 across the carriage are a pair of parallel channels 54 serving as bracing members. In addition, these channels provide the support for the pivotally mounted plate catch 55 having a shoulder receivable in an opening 56 in the face plate 42 of the carriage 11 so that it may selectively engage a catch notch 57 in the fitting plate 44 which in turn is slidable along the upper tracks. A spring 58 urges the plate catch member 55 to-

ward the face plate 42 so that it may automatically engage the catch notch 57 in the fitting plate 44 when the latter is raised to its uppermost position along the tracks 16. (See Figs. 5 and 6.) This catch thus retains the entire movable structure against accidental or unintended movement while located on the face plate 42 of the carriage 11. A lanyard 59 is attached to the plate catch 55 for manually releasing it.

The channels 54 also support the two double sheave blocks 60 and 61. The two sheaves D and G are rotatably mounted on the shaft 60a of the double sheave block 60 and the two sheaves E and H are similarly mounted in the double sheave block 61.

The lower portion 17 of the guideway 15 is also comprised of a pair of parallel tracks secured to the side 13 of the ship at opposite sides of the intake opening 18 and extend upwardly therefrom beyond the top deck line 12 of the ship to a point slightly above the bottom portion of the face plate 42. These tracks are so mounted as to be in alignment with the upper tracks 16 secured to the face plate 42. (See Figs. 1 and 2.) Thus, when the carriage is moved from its inboard position as shown in Fig. 3 to its lowest position as shown in Fig. 2 whereby the face plate 42 is aligned with the side 13 of the ship, the tracks 16 and 17 form the guideway 15 along which the fitting plate 44 may slide.

The portion of tracks 17 which extend slightly above the lower portion of the face plate 42, serve as a carriage stop and enable rapid, easy alignment of the two divisible pairs of tracks 16 and 17.

Plate stops 64, secured to the ship's side 13 below the intake opening 18 and between the lower tracks 17 are so positioned that when the fitting plate 44 rests on the stops, the upper end of the suction pipe 31 is substantially aligned with the intake opening 18 and remains so aligned during hydraulic loading of the ship. It is preferred that the upper and lower tracks 16 and 17 be flanged to engage the edges of the fitting plate 44 which is slidably mounted between these tracks. Thus, when the upper end of the suction pipe 31 is substantially aligned with the intake opening 18, it is also sufficiently flush therewith and no connection between the suction pipe 31 and the intake opening 18 is necessary during hydraulic loading. As a result, the upper end of the suction pipe 31 may be moved from an inboard position as indicated in Figure 3 to a position along the side 13 of the ship and then lowered so as to be substantially aligned flush with the intake opening 18 in two separate, sequential steps.

To move the carriage over the I-beams 19 and slide the fitting plate 44 along the upper and lower tracks 16 and 17, respectively, a single line pulley system is preferred. However, this invention is not to be construed as limited to this particular means as other well-known means may be employed. As shown in Figs. 1 and 2, one end of the pulley line 65 is attached to the fitting plate 44 by tying it around the keyed pin 66 inserted in the upper part of the fitting plate 44. From this pin the pulley line 65 is passed over and around the following sheaves successively: A, B, C, D, E, F, G, H, I and K, and from K the line 65 then leads to a drum 67 of the single drum winch 68 (See Figs. 1-7). As described above, sheaves A, C, D, E, G and H are mounted on the carriage 11, sheave B is located on the fitting plate 44 which is adapted to slide along the guideway tracks 15 and sheaves F, I

and K are mounted on the way 10. This particular arrangement of sheaves permits movement of the carriage 11 over the way and the fitting plate 44 along the upper and lower tracks 16 and 17 by the use of a single pulley line 65 operated by the single drum winch 67.

The general method of operating the apparatus is as follows:

After hydraulic loading of the ship has been completed, the fitting plate 44 is raised along the lower tracks 17 by winding the single line pulley 65 on the winch drum 67 until the catch notch 57 in the fitting plate 44 is engaged by the plate catch 55. During this operation, the carriage 11 is prevented from moving up the inclined I-beams 19 by the carriage catch members 36a and 36b whose hook-shaped arms 37a and 37b engage the slots 41a and 41b in the top flanges 26a of the I-beams 19. With the fitting plate 44 retained on the carriage face plate 42, the pulley line 65 is slackened off to permit disengagement of the carriage catch members 36a and 36b from the slots 41a and 41b. By further winding this line about the winch drum 67, the carriage 11 is pulled inboard over the I-beams 19 to its uppermost position where the hook-shaped arms 37a and 37b of the carriage catch members 36a and 36b are made to engage the slots 41c and 41d of the I-beams 19. While the carriage is being moved over the I-beams 19, stops 69 located at the top of the face plate 42 prevent the fitting plate 44 from further movement upwards. It is to be noted that during this operation the lower end of the suction pipe 31, not shown in the drawings, is simultaneously being raised and moved inboard by an appropriate means such as a stiff-legged crane of the standard type used on sand carrying ships. In order to position the upper end of the suction pipe 31 with respect to the intake opening 18, the above procedure is merely reversed.

Having described the invention as related to the embodiments shown in the accompanying drawings, it is intended that the invention be not limited to any of the details of description unless otherwise specified, but rather be construed broadly within its spirit and scope as set out in the accompanying claims.

I claim:

1. Apparatus for positioning equipment relative to the side of a ship, comprising: a way mounted on a deck of the ship, the way having one end substantially adjacent the side of the ship and extending inwardly therefrom; a carriage mounted on the way for movement between a position with a face of the carriage substantially aligned with the side of the ship and a position inwardly therefrom; a guideway having an upper portion mounted on the face of the carriage and a lower portion secured to the side of the ship, said portions being divisible from each other; a plate to which equipment may be secured, said plate being positioned for travel along the guideway; a carriage stop for arresting the movement of the carriage toward the side of the ship when the upper and lower portions of the guideway are substantially aligned; a carriage catch for preventing movement of the carriage when the face is substantially aligned with the side of the ship and while the plate is located along the lower portion of the guideway; and means for moving the carriage over the way and for moving the plate along the guideway when the upper and lower portions thereof are in substantial alignment.

2. The positioning apparatus as set forth in claim 1 wherein the way slopes downwardly toward a side of the ship and a single line pulley system is used to move the carriage over the way and the plate along the guideway.

3. Apparatus for positioning equipment relative to the side of a ship, comprising: a way mounted on a deck of the ship and sloping downwardly toward a side of the ship, the way having its low end substantially adjacent the side and extending inwardly therefrom; a carriage mounted on the way for movement between a position with a face of the carriage substantially aligned with the side of the ship and a position inwardly therefrom; a guideway having an upper portion mounted on the face and a lower portion secured to the side of the ship, said portions being divisible from each other; a plate to which the equipment may be secured, said plate being positioned for travel along the guideway; a releasable plate catch for retaining the plate in the upper portion of the guideway; and a single line pulley system for moving the carriage over the way and for moving the plate along the guideway.

4. In a ship having a dredge pump intake opening in its side and a suction pipe for conducting a mixture of sand and water from the bottom of a body of water to the opening, apparatus for positioning one end of the suction pipe relative to the intake opening, comprising: a way mounted on a deck of the ship and sloping downwardly toward a side of the ship, the way having its low end substantially adjacent the side and the other end located inwardly therefrom and said side having an intake opening therein; a carriage slidably mounted on the way for movement from a position with a face substantially aligned with the side of the ship to a position inwardly therefrom; a pair of substantially parallel continuous tracks having an

upper portion mounted on the face of the carriage and a lower portion separable from the upper portion and fixed in position along the side of the ship at opposite sides of the intake opening; a plate slidably mounted between the tracks, said plate having one end of the suction pipe mounted thereon and having an opening therein substantially aligned with the end of the suction pipe; a carriage stop for arresting the movement of the carriage toward the side of the ship when the upper and lower portions of the tracks are in substantial alignment; a carriage catch adapted to retain the carriage in a fixed position when the face is substantially aligned with the side of the ship, said catch adapted to be released when the plate is located along the upper portion of the tracks; a plate catch for retaining the plate in the upper portion of the tracks, said plate catch adapted to be released when the upper and lower portions of the tracks are in substantial alignment; a plate stop for arresting the movement of the plate along the track so as to substantially align the plate opening flush with the intake opening; and a single line pulley system for moving the carriage over the way and for moving the plate along the tracks when the upper and lower portions thereof are substantially aligned.

ROY A. BRINKMAN.
